UNITED STATES PATENT OFFICE.

LA ROY E. TAIT, OF REDCLOUD, NEBRASKA.

FEED-GAGE.

No. 808,953.

Specification of Letters Patent.

Patented Jan. 2, 1906.

Application filed May 25, 1905. Serial No. 262,286.

To all whom it may concern:

Be it known that I, LA ROY E. TAIT, a citizen of the United States, residing at Redcloud, in the county of Webster and State of Nebraska, have invented a new and useful Feed-Gage; and I do hereby declare the following to be a full, clear, and exact description of the invention, such as will enable others skilled in the art to which it appertains to make and use the same.

The invention relates to feed-gages for platen printing-presses, and has for its object to provide an exceedingly simple, inexpensive, and durable device of this character provided with means for doing positive and accurate register work which is so essential in color-work.

A further object of the invention is to provide a simple and efficient clamp whereby the feed-gage may be readily clamped to the tympan-sheet without injuring said sheet, said clamp being adapted to clamp or release in a most simple yet effective manner.

With these and other objects in view my invention consists in the novel construction and arrangement of parts hereinafter described and shown, and particularly pointed out in the appended claims.

In the drawings forming part of this specification, and in which like numerals of reference designate corresponding parts, Figure 1 is a plan view of a feed-gage constructed in accordance with my invention and shown applied. Fig. 2 is a perspective view of the device. Fig. 3 is a side elevation. Fig. 4 is a view of an ordinary feed-gage having my clamping device applied thereto. Fig. 5 is a perspective view of my clamp. Fig. 6 is a detail perspective view of the upper member 4. Fig. 7 is a longitudinal-sectional view of the feed-gage.

Referring to the drawings, 1 designates the platen of a printing-press, and 2 the tympan-sheet to which my device is designed to be attached, and 3 the sheet of paper which is fed to the printing-press.

The gage is constructed of sheet-copper or other suitable metal. The gage is composed of sheet metal having upper and lower members 4 and 5. Lugs 6 and 7 are formed out of the upper member 4, as shown in Figs. 1

and 2 of the drawings, and said lugs have openings or perforations 8 for the reception of a pin on which an approximately L-shaped lever is mounted. The L-shaped lever 9 engages a spring 10, and the lower part of said lever is engaged by an inclined portion 11 of the member 4, whereby said lever is held in engagement with said spring. A lug 12 is also formed integral with the member 4, against which the sheets of paper are fed in printing. In practice the lever 9 is engaged by the gripper-bar, which presses it down, whereby the lower part of said lever is adapted to shove the sheet of paper out to the register-line, whereby accurate work is accomplished.

My feed-gage is adapted to be secured to the tympan-sheet by means of a clamp consisting of upper and lower members 12 and 13 and is provided with a shank 14 and is secured to the feed-gage by means of a rivet 15, which pierces the upper and lower members of the feed-gage and the lower member of the clamp and which holds them securely together. The clamp is provided with an upward projection 16, by which it is swung into and out of engagement with the feed-gage, as desired.

The feed-gage is secured to the tympan-sheet by means of the clamp as follows: A slit 17 is cut into said tympan-sheet, and said tympan-sheet is engaged by the upper and lower members of the feed-gage, and the said members are engaged in like manner by the clamp, whereby the device is firmly secured to the tympan-sheet.

What I claim is—

1. A feed-gage consisting of upper and lower members, a lever mounted in a pair of upturned projections formed integral with said upper member, substantially as shown, a spring mounted on the rear portion of said upper member and engaging said lever, a lug also formed integral with said upper member and adapted to limit the action of said spring-pressure, said lever being adapted to engage the gripper-bar of a printing-press, substantially as and for the purpose described.

2. A feed-gage having upper and lower members, said members being adapted to receive a tympan-sheet between them, a sheet-

metal clamp bent upon itself, having upper and lower members and adapted to receive said first-named members between them, substantially as described.

5 3. A feed - gage having a clamp provided with a shank, said shank being pivoted to the inner face of said feed-gage and capable of a horizontal swinging movement, whereby it is

brought into and out of engagement with the feed-gage, substantially as described. 10

In testimony whereof I have hereto affixed my signature in the presence of two witnesses.

LA ROY E. TAIT.

Witnesses:

H. C. LETSON,
W. A. SHERWOOD.
